UNITED STATES PATENT OFFICE.

JOHN F. O'CONNOR, OF CHICAGO, ILLINOIS, ASSIGNOR TO WILLIAM H. MINER, OF CHAZY, NEW YORK.

RECORDING DEVICE.

1,290,318.

Specification of Letters Patent.

Patented Jan. 7, 1919.

Application filed August 20, 1917. Serial No. 187,293.

To all whom it may concern:

Be it known that I, JOHN F. O'CONNOR, a citizen of the United States, residing at Chicago, in the county of Cook and State of Illinois, have invented a certain new and useful Improvement in Recording Devices, of which the following is a full, clear, concise, and exact description, reference being had to the accompanying drawings, forming a part of this specification.

This invention relates to improvements in recording devices.

Heretofore, the generally accepted method of testing the actions of draft gears or shock absorbing mechanisms employed on railway cars and the like has been the so-called "drop hammer test". By this method, the shock absorbing mechanism to be tested is placed upon an anvil and a heavy weight or hammer, generally 9,000 lbs., is dropped from different heights onto the shock absorbing mechanism and the effects thereof noted. In my Patent No. 1,217,984, issued March 6, 1917 for means for recording actions of railway draft gears, I have fully disclosed a recording mechanism for determining the rate of deceleration of such a falling body and the actual work performed by the shock absorbing mechanism during the absorption of the blow, as will more fully appear from reference to said patent. As is well known, the intervals of time during which the blows are absorbed by shock absorbing mechanisms, both in the drop hammer tests and in actual service, are almost infinitesimal, numerous experiments having determined that the interval of time is generally less than one-tenth of a second.

In the drop hammer tests, it is obvious that the falling body is a solid, substantially non-yieldable mass. When, however, the shock absorbing mechanism is applied to a car and the car is brought to rest through the intermediary of said shock absorbing mechanism, there is a somewhat different action which takes place and which cannot be accurately imitated by the drop hammer tests. In a moving car, there are several distinctive parts thereof which are decelerated under different conditions due to the fact that there is relative movement between said distinctive parts during the deceleration period. For instance, it is obvious that when the car is loaded, a large proportion of the load will tend to shift

relative to the rigid frame or superstructure of the car during the act of deceleration. Similarly, there is relative movement between the car framework and the trucks, and in addition, there is also relative movement between the wheels and associated axles of the car and the frame members of the truck. In view of the fact that the rigid framework of the car, the load, the truck elements and the wheels are of different weights, it is obvious that the forces required to decelerate the various component parts vary according to the mass or weight of each of the parts and it is these variable factors which are not accurately recorded in the drop hammer tests.

The object of my invention is to provide an arrangement for accurately recording the deceleration of the component parts of a car during the compression of the shock absorbing mechanism thereon and to thereby obtain an accurate record of the performance of the shock absorbing mechanism during actual service conditions.

In the drawings forming part of this specification, Figure 1 is a side elevation of two cars with my improvements arranged in connection therewith. Fig. 2 is a top plan view of the structure illustrated in Fig. 1. Fig. 3 is a longitudinal, vertical, sectional view, upon an enlarged scale, illustrating the details of construction of what may be termed the test car and my recording device. Fig. 4 is an end elevation of the so-called test car and corresponds to the section line 4-4 of Fig. 3. Fig. 5 is a horizontal, sectional view, taken substantially on the line 5-5 of Fig. 4. And Fig. 6 is a detailed elevational view of the recording mechanism proper.

In said drawings, A designates what, for convenience, may be termed the test car and B a fixed or bumper car by which the moving test car A is adapted to be brought to rest, as hereinafter described. Said cars are arranged on the same track which is preferably inclined so that the test car A may be made to acquire any desired speed in carrying out the tests, the speed of course depending upon the grade of the track and the distance through which the car A is permitted to accelerate before engaging the bumper car B.

The bumper car B is provided with a shock absorbing mechanism which is indi-

cated conventionally by dotted lines most clearly in Fig. 3 and from which extends a dummy coupler 10. Secured to the dummy coupler 10 is the recording mechanism proper, designated generally by the reference C. Said recording mechanism C, as shown, is substantially the same as that described in my said Patent No. 1,217,984 and briefly described, includes a rotatable drum 11 on which is carried the record sheet, a motor 12, and a stylus of any suitable form 13. For a more complete description of the recording mechanism and the method of reading the record obtained thereby, reference is hereby made to said Patent No. 1,217,984 and also to my later Patent No. 1,225,996 for indicators, issued May 15, 1917.

The test car A, as shown, is so designed as to reproduce as nearly as possible, the average conditions incident to the stopping and starting of a loaded freight car. As shown, the test car A comprises an underframe structure 14 from which extends the body 15 and which carries a comparatively small proportion of sand or gravel 16. Mounted within the gravel or sand 16 is a large trough-shaped element 17 loaded with sand or gravel 18, and it will be noted that the ends of the member 17 are inclined to the vertical at an angle corresponding to the natural slope of the sand or gravel employed so that, when the moving car is suddenly brought to rest, the action of the member 17 carrying the load 18 will tend to shift as an entirety as it would if the car were loaded in actual practice with similar material. The proportion of the load carried by the member 17 represents the shifting portion of an ordinary loaded car and the portion 16 represents that proportion of the load which will not have any appreciable displacement during sudden deceleration. In carrying out my invention, the weight of the member 17 and its load will preferably be made four times that of the rigid frame, body and portion 16.

The car A is of course provided with the usual body bolsters 19 to which the bolsters 20 of the trucks are pivotally connected, and associated with the truck bolsters 20 are the usual truck frame members 21. Co-operating with the truck frames 21 are the usual sets of axles 22 and the car wheels 23, together with the journal boxes 24. The car will also be provided with the usual brake mechanism and parts accessory to the underframe and truck frames.

The weight of the wheels, axles and journal boxes, which may be considered as movable and acting as a unit, will approximate 7,500 lbs., and the weight of the truck frames, brake rigging and accessories thereto will approximate 5,000 lbs., and in carrying out my invention, the weight of the frame superstructure with the load portion

16 will approximate 25,000 lbs., and the main or shiftable portion of the load 18 will approximate 100,000 lbs. The foregoing makes a grand total of 137,500 lbs.

The car A is provided with a shock absorbing mechanism S mounted in the usual manner and indicated conventionally by the dotted lines in Fig. 3. Said shock absorbing mechanism S is adapted to be compressed between followers in the usual manner when the moving car is brought to rest and, for actuating the shock absorbing mechanism, another dummy coupler 25 is provided, the same being adapted to coöperate with the dummy coupler 10, as will be obvious.

In order to reduce the effect of the various component parts of the car to a common factor for actuating the recording mechanism C, I employ the following means: Secured to the end of the car A adjacent the dummy coupler 25 is a bracket 26 to which is pivotally connected a lever 27. The lever 27 at its upper end is in turn pivotally connected to a link 28 which extends through a tube 29 in the section 16 of the load in order to permit movement of said link 28. At its inner end, the link 28 is rigidly connected to the member 17 which carries the shiftable load 18. Referring to Figs. 3 and 4, it will be seen that a rod 30 is employed which extends from the truck bolster and is pivotally connected to the upper end of a relatively short link 31. From the adjacent car axle extends a rod 32 which is pivotally connected to the lower end of said link 31. At its inner end, the rod 32 is provided with a suitable ring portion which encircles the axle. The link 31 intermediate its ends, and at a distance three-fifths of its length from the upper pivotal connection with the rod 30, is connected to the lower end of a bar 33. At its upper end, the bar 33 is pivotally connected to a short link 34 which in turn is pivotally connected to the lever 27, as indicated at 35, the pivotal connection 35 being at such a point that the portion of the lever 27 thereabove is four times the length of the portion therebelow. To prevent the link 31, bar 33 and rods 30 and 32 from being displaced laterally, a bracket 36 is extended downwardly from the buffer block 37 of the car, which bracket 36 has a slot 38 in its lower end within which freely works back and forth a stud or pin 39 carried by the bar 33. As most clearly shown in Fig. 5, the bar 33 is provided with a laterally extended flange 40 to actuate the stylus 13 of the recording mechanism C.

Said flange 40 is located in the same horizontal plane as the center of mass of all the component parts of the car considered as a unit and further, is so positioned with the face of the dummy coupler 25, that when the two dummy couplers 10 and 25 engage, 130

the flange 40 will engage the stylus 13 and move the same over the recording drum, as will be understood.

In making a test, the car A is permitted to acquire any desired speed and to be brought to rest by impact against the stationary bumper car B. When the impact takes place, that is, when the dummy couplers 10 and 25 engage, it is obvious that the stylus 13 will be actuated due to the fact that there is thereafter no relative movement between the recording drum 11 and the dummy coupler 25 but there is relative movement between said drum and all of the parts of the car A with the exception of said dummy coupler 25. In other words, assuming that the shock absorbing mechanism S is one which is provided with a three-inch movement, that is, the mechanism can be compressed for a distance of three inches, it is obvious that the car framework, load trucks, etc., considered as an entirety, can move toward the dummy coupler 25 a distance of three inches, and it is during this relative movement between the dummy coupler 25 and the car that the deceleration of the latter occurs and the work of the gear is performed.

The ratio of the arms or levers 27 with respect to the point 35 being 4:1 and the ratio of the weights or masses of the shiftable load 18 and the car underframe superstructure 14, 15 and 16 being 4:1, it is apparent that the effect produced by said two component parts of the car in moving the links 34 will be reduced to a common result. Or, stated in another manner, the weight of the shiftable load 18 times the distance through which it moves the link 34 will equal the weight of the car underframe, superstructure and load portions 16 times the distance through which they move the link 34. Similarly, with the link 31 proportioned 3:2, as hereinbefore described and the weights of the wheels, axles and journal boxes considered as a unit and of the truck frame, bearings and accessories, considered as a unit, being as 3:2, it is obvious the effect produced by said component parts of the car will be reduced to a common factor at the lower end of the bar 33. The combined weight of the wheels, axles, truck frames, boxes, bearings, brakes and accessories, etc., which determines the movement of the lower end of the bar 33, totals 12,500 lbs., which is one-tenth of the combined weight of the car frame, superstructure and load which totals 125,000 lbs. Therefore, the distance from the flange or arm 40 of the bar 33 to the lower end of the bar 33 is made 10 times the distance between said flange or arm 40 and the pivotal connection of the upper end of the bar 33 with the link 34. In this manner, the effect of all the component parts of the car is reduced to a

single force applied to the stylus 13 and consequently the actual kinetic shocks of the component parts of a loaded car, as absorbed by the shock absorbing mechanism S, are accurately transferred to the recording device C.

Although I have herein shown and described what I now consider the preferred manner of carrying out my invention, it is obvious that various changes and modifications may be made in the details of construction without departing from the spirit of the invention and I contemplate all changes, modifications and arrangements that come within the terms of the claims appended hereto.

I claim:

1. In an arrangement for recording the deceleration of a mass composed of a plurality of relatively movable portions, the combination with a recording device proper including a record sheet and a stylus; of means, interposed between and operatively associated with said recording devices and said mass portions, for causing relative movement between said stylus and sheet, said means including a system of compensating elements arranged to produce a movement of one of them proportional to the combined effective movements of all portions of the mass.

2. In a device of the character described, the combination with a mass composed of a plurality of portions of different characteristics, the aggregate action of which under shocks determine the action of the mass as an entirety; of recording means proper; and means, including a plurality of links and levers of different arm ratios, associated with said mass for actuating said recording means and proportionally indicating the effects of said different portions of the mass.

3. In an arrangement for determining the deceleration of a movable car by a shock absorbing mechanism, the combination with a car having a shock absorbing mechanism thereon; of a recording device; and means, including an element for directly engaging said recording devices, carried by said car, and connected to the component parts thereof, for actuating said recording device during the compression of said shock absorbing mechanism, said means being so arranged that the result and effect of the product of the weight and distance traveled by each component part of the car during deceleration are ultimately transmitted to the recording device through said elements and equalized.

4. The combination with a loaded car having a shock absorbing mechanism thereon; of a recording mechanism proper, means to actuate the shock absorbing mechanism to decelerate the car; a member carried by the car for actuating said recording mecha-

nism during the act of deceleration; and means interposed between said member and the different component parts of the car and its load for moving said member relatively 5 to one element of the shock absorbing mechanism inversely proportional to the weight of each of said component parts.

5. In a device of the character described, the combination with a car having a shift-
10 able load; of a shock absorbing mechanism mounted on said car, said shock absorbing mechanism including a coupler; of a bar adapted to actuate the recording mechanism proper; and connections between said bar 15 and the component parts of the car and load for actuating said bar in accordance with the weights of the component parts of the car during actuation of the shock absorbing mechanism in decelerating the car.

6. In a device of the character described, 20 the combination with a car having a shock absorbing mechanism mounted thereon, said mechanism including a coupler for actuating the mechanism; of an element adapted to actuate a recording mechanism; and a system of links and levers interposed between said element and the component parts of the car so arranged that, the product of the weight of each component part times the effective distance through which it moves said 25 element is equal to the product of the weight of any other component part times the distance through which the latter actuates said element.

In witness that I claim the foregoing I 30 have hereunto subscribed my name this 4 day of Aug., 1917.

JOHN F. O'CONNOR.
